UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,929, dated November 28, 1893.

Application filed October 14, 1893. Serial No. 488,178. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of bunches of flowers and leaves of violets and forget-me-nots tied 10 with small ribbons and arranged at regular distances apart over the surface of the paper as represented in the accompanying drawing. The border or upper portion of the design is 15 formed of bunches of the same flowers with interlacing lines of ribbon and flowers and leaves as shown, with an ornamental band composed of parallel lines and small ornaments between said lines forming the lower edge of the border.

What I claim is—

1. The design for wall paper herein shown and described.
2. In the design for wall paper, the border herein shown and described.

Witness my hand this 10th day of October, 20 1893.

CHARLES BOOZE.
